[57] CLAIM

The ornamental design for a surface mount electrical receptacle, as shown and described.

DESCRIPTION

FIG. 1 is a front plan view of the surface mount electrical receptacle of the present invention;

FIG. 2 is a back plan view of the surface mount electrical receptacle of FIG. 1, with the rectangular member shown rotated 180 degrees and moved to the opposite side elevation;

FIG. 3 is a left side plan view of the surface mount electrical receptacle of FIG. 2, the right side plan view being substantially a mirror image thereof;

FIG. 4 is a top plan view of the surface mount electrical receptacle of FIG. 1;

FIG. 5 is a bottom plan view of the surface mount electrical receptacle of FIG. 2; and,

FIG. 6 is a back plan view of the assembled surface mount electrical receptacle of FIG. 2.

The broken lines shown in FIGS. 1, 2, 3, 5, and 6 are frangible lines.
